UNITED STATES PATENT OFFICE

159,805

PLATE OR SIMILAR ARTICLE

Virginia Hamill, Stamford, Conn.

Application October 11, 1949, Serial No. 5,432

Term of patent 14 years

(Cl. D44—15)

To all whom it may concern:

Be it known that I, Virginia Hamill, a citizen of the United States, residing at West Hill Road, Stamford, Connecticut, have invented a new, original, and ornamental Design for a Plate or Similar Article, of which the following is a specification, reference being had to the accompanying drawing, forming a part hereof.

The sole figure is a top plan view of a plate showing my new design. The dominant feature thereof resides in a floral surface decoration as shown.

I claim:

The ornamental design for a plate or similar article, as shown and described.

VIRGINIA HAMILL.
